UNITED STATES PATENT OFFICE.

RALPH M. LICKLEY, OF EAST CLEVELAND, OHIO, ASSIGNOR TO JOHN G. TALMAGE, OF CLEVELAND, OHIO.

MEANS FOR LUBRICATING LOCOMOTIVE-CYLINDERS.

1,188,796.

Specification of Letters Patent. Patented June 27, 1916.

Application filed October 21, 1915. Serial No. 57,192.

To all whom it may concern:

Be it known that I, RALPH M. LICKLEY, a citizen of the United States, residing at East Cleveland, in the county of Cuyahoga and State of Ohio, have invented a certain new and useful Improvement in Means for Lubricating Locomotive-Cylinders, of which the following is a full, clear, and exact description, reference being had to the accompanying drawings.

The object of this invention is to provide a simple and efficient system for maintaining proper lubrication in the cylinders of locomotives when the engine is running with the throttle closed. At such periods, as is well known, the piston acts as a pump tending to create a vacuum and draw into the cylinder products of combustion from the stack which char the lubricant and cause trouble- some deposits in the cylinders.

My invention provides a simple automatic valve and piping for locomotives which enables steam in proper quantity to be automatically fed to the cylinders when the locomotive is running by gravity or momentum with the throttle closed, thus preventing the formation of vacuum, preserving the lubricant which is already in the cylinders, and further lubricating the pistons with the steam thus supplied.

A further object of my invention is to enable the steam which I supply to the cylinders when the throttle is closed to carry the lubricating oil intermingled with it.

A still further object is to enable the oil so supplied to also lubricate the automatic valve which controls the admission of the steam.

The drawings illustrate my invention in a preferred form.

Figures 1 and 2 are respectively a plan and a side elevation of a locomotive equipped with my invention, the lubricating parts being shown in full lines and the general structure of the locomotive in broken line. Fig. 3 is an end elevation of the cylinder, steam chest and associated parts, this view being taken at the rear of the right hand cylinder look-

ing forward, with the heads of the cylinder and steam chest removed, and the dry pipe 50 and the pipes communicating with the automatic valve broken away. Fig. 4 is a vertical section along the axis of the automatic valve.

As shown in the drawing, A indicates the boiler, B the steam dome, C the throttle valve, D the throttle lever connected therewith, E the dry pipe leading from the steam dome to the steam chest F which contains the distributing valve, and G the cylinder, 60 these members being illustrative of the corresponding parts in any locomotive.

In each of the views, 10 indicates the casing of my automatic valve. This casing is suitably connected with the steam chest and 65 adapted to discharge thereinto. As shown, the casing has an extension 11 at its lower portion which is externally threaded and may thus screw into a suitable boss f carried by the wall of the steam chest. The 70 casing has a lateral tubular extension providing an intake 12, and between this intake and the exit passage 13 is an annular valve seat 14 controlled by a disk plug 20. The extension 12 is connected with the source of 75 steam supply independently of the throttle. For this purpose I have shown a pipe 30 secured by a coupling 31 to the casing extension 12, and at its other end connected with the steam dome B.

I prefer to provide an automatic valve on each steam chest, each of which is fed by a pipe 30, and it is convenient to bring these two pipes together to a T connected with or forming part of any suitable shut-off valve 85 32 which is in communication with the interior of the steam dome. This shut-off valve is normally open, but may be closed when the locomotive is run into the round-house.

The position of the disk plug 20 with reference to the seat 14 determines the admission of live steam through the pipe 30 to the steam chest. This plug is controlled by the pressure conditions in the steam chest in such manner that the automatic valve remains closed in normal running of the en-

gine, but, when the pressure in the chest drops to a certain predetermined amount (which is still above the atmospheric pressure) the plug rises and admits live steam to the chest, thus preventing the formation of vacuum and thus preserving the lubrication in the cylinder. The valve construction which enables this automatic pressure-operation will now be described. The valve casing 10 has above the inlet 12 a cylinder 15 and above this a larger cylinder 16, the top of the casing being closed by a suitable cover 17. Within the cylinder 15 is a piston 21 and within the cylinder 16 is a larger piston 22, both of these pistons being rigidly connected with the valve plug 20. The connection shown consists of an axial stem 23 which has an axial opening 24 extending through it from end to end. The piston 21 is slightly 20 larger than the disk 20, while the piston 22 is materially larger than the piston 21. The pistons are provided with any usual packing, and a suitable vent 18 is provided between the pistons to allow the escape of any 25 steam passing the packing. By reason of the slightly larger area of the piston 21 over the disk 20, it will be seen that the live steam constantly admitted to the entrance 12 tends slightly to raise the valve plug from 30 its seat. Steam chest pressure acting upwardly on the under side of the valve plug also tends to raise it, but this same fluid under pressure passing upwardly through the opening 24 acts downwardly on the greater 35 area of the piston 22. The excess of this area over the area of the plug is materially greater than the excess of the piston 21 over that plug. Accordingly, the normal steam-chest pressure causes a downward pressure 40 on the plug and piston member much greater than the upward pressure of the live steam in the pipe 30, and therefore the valve is held seated. Now, when the throttle is closed, the pressure in the steam chest rapidly 45 drops, and, when it reaches the desired minimum (preferably a few pounds per square inch above the atmosphere), the effective downward pressure has been so reduced that it is more than counter-balanced by the 50 boiler pressure acting upwardly against the small excess of area of the piston 21. Accordingly, at this point the piston and plug member rises and live steam is admitted from the pipe 30 past the plug into the 55 steam chest. This live steam prevents the formation of a vacuum, and the consequent deterioration of the lubricant, and also it-self lubricates the engine pistons.

The piping provided and the passageways 60 of my valve are preferably of such size that sufficient steam may be fed, as described, to the cylinders to prevent the formation of a vacuum when the locomotive is running at its highest permissible speed with the

throttle closed. As the speed is reduced the 65 pressure will rise in the steam chest, and this pressure, being transmitted through the central passageway 24 to the top of the larger valve piston 22, acts to move the valve plug in the closing direction, thus reducing the 70 supply and correspondingly reducing the pressure. Accordingly, the effect is to maintain the valve with such an opening as will supply the desired amount of steam to the 75 cylinders irrespective of the speed. 75

It has been found that lubricating oil admitted with steam is more effectively distributed than if admitted in a continuous liquid stream. To enable the oil to be so admitted with the steam supplied by my attachment, and to enable this oil to perform the further function of lubricating the automatic valve, I prefer to connect the regular lubricating pipe of the locomotive with the automatic valve, and feed the oil continuously to the valve chest through the tubular opening at the axis of the automatic valve. The lubrication feed referred to is shown in the drawings, wherein 40 designates the usual lubricating pipe of the locomotive. At 80 its upper end this pipe is connected with a suitable pressure lubricator 41 which is connected by a pipe 42 with the top of the boiler under the control of a shut-off valve 43. I simply disconnect the forward end of 85 this pipe 40 from the steam chest and connect it to the top of the automatic valve. A suitable choke is provided limiting the quantity of oil supplied, and this choke may conveniently be located in a nipple between the 90 pipe 40 and the top of the valve casing. This is the construction shown in Fig. 4, wherein 45 is the nipple screwed into the valve cover and having a reduced bore at 46 and at its upper end connected by a flange 105 coupling 48 to the pipe 40.

Irrespective of whether the automatic valve be open or closed, the boiler pressure acts on the lubricator and forces the oil through the pipe 40 and through the choke 110 46, so that a small quantity continuously passes through the bore 24 into the valve chest. This oil becomes scattered in the chamber above the piston 22 and thus results in the lubrication of that piston and 115 the piston 21. In ordinary running under pressure, the steam from the dry pipe E enters the valve chest at the side of the entrance from the automatic valve, and thus this live steam catches the oil and distributes 120 it. When the throttle is closed the steam entering the pipe 30 and passageway 13 also catches this oil and effectively distributes it.

Reference is hereby made to my copending application No. 57,191 on a valve, filed 125 concurrently herewith, for claims on the internal construction of the particular automatic valve shown in Fig. 4.

Having thus described my invention, what I claim is:

1. In a system for lubricating locomotive cylinders, the combination with a steam chest and boiler, of an automatic valve connected with the steam chest and having a connection with the boiler and adapted to open or close communication between said connections, a lubricator connected with the 10 boiler, and a discharge pipe from the lubricator connected with the automatic valve.

2. The combination, with the steam chest and boiler of a locomotive, of an automatic valve connected with the steam chest, a supply pipe for the automatic valve connected with the boiler, a lubricator connected with the boiler, a discharge pipe from the lubricator connected with the automatic valve, and means whereby the automatic valve is 20 opened consequent upon reduction in pressure in the valve chest.

3. In a system for lubricating locomotive cylinders, the combination with a steam chest and boiler, of an automatic valve connected with the steam chest and having a connection with the boiler, said automatic valve having a valve plug and an operating piston therefor, a lubricator connected with the boiler, and a discharge pipe from the 30 lubricator connected with the automatic valve.

4. The combination, with the steam chest and boiler of a locomotive, of an automatic valve connected with the steam chest, a supply pipe for the automatic valve connected with the boiler, said automatic valve being adapted to open or close communication between said supply pipe and steam chest, a lubricator connected with the boiler, a discharge pipe for the lubricator connected with an automatic valve, and a passageway in an automatic valve adapted to transmit lubricant to the valve chest whether the automatic valve be opened or closed.

45 5. The combination, with the steam chest and boiler of a locomotive, of an automatic valve having a casing secured to the steam chest, a pipe connecting the automatic valve with the boiler, a valve plug between the entrance for such pipe and the discharge into the valve chest, a pair of pistons of different area adapted to cause the valve to remain seated in normal running but to be lifted from its seat consequent upon the reduction in pressure in the valve chest to a predetermined minimum, a tubular opening through such pistons and valve plug, a lubricator connected with the boiler, and a discharge pipe for the lubricator discharging into the 50 casing of the automatic valve.

60 6. The combination with a steam chest and boiler of a locomotive, of an automatic valve having a casing connected with the steam chest, a pipe connecting the automatic valve

with the boiler, a valve plug between the entrance for such pipe and the discharge into the valve chest, means for causing the valve to remain seated in normal running but to be lifted from its seat consequent upon reduction in pressure in the valve chest to a predetermined minimum, a discharge conduit from the lubricator to the automatic valve, and a choking device in said conduit.

7. The combination with a steam chest and boiler of a locomotive, of an automatic valve having a casing secured to the steam chest, a pipe connecting the automatic valve with the boiler, a valve plug between the entrance for such pipe and the discharge into the valve chest, a pair of pistons of different area one above the other and connected with the valve plug and adapted to cause the same to remain seated in normal running but to be lifted from its seat consequent upon the reduction in pressure in the valve chest to a predetermined minimum, a tubular opening through such pistons and valve plug, a lubricator connected with the boiler, a discharge pipe for the lubricator discharging into the casing of the automatic valve above the upper piston, and a choking device in the conduit from the lubricator to the interior of the automatic valve.

8. In a lubricating system, the combination with a cylinder, valve chest, dry pipe, throttle and boiler of a locomotive, of an automatic valve connected with the steam chest and with the boiler independently of the throttle, said automatic valve having an internal valve seat between its admission pipe and the valve chest, a plug for said valve seat, a piston connected with the plug on the opposite side of the admission to the automatic valve, said piston being slightly larger than the plug, whereby the live-steam pressure tends to unseat said plug, and means for enabling the normal steam chest pressure to seat the plug.

9. In a lubricating system, the combination with a cylinder, valve chest, dry pipe, throttle and boiler of a locomotive, of an automatic valve connected with the steam chest and with the boiler independently of the throttle, said automatic valve having an internal valve seat between its admission pipe and the valve chest, a plug for said valve seat, a piston connected with the plug on the opposite side of the admission to the automatic valve, said piston being slightly larger than the plug, a still larger piston connected with said plug, and a passageway for enabling the steam chest pressure to act on the larger piston in the direction to seat the plug.

10. In a lubricating system, the combination with a cylinder, valve chest, dry pipe, throttle and boiler of a locomotive, of an automatic valve connected with the steam

4
chest and with the boiler independently of the throttle, said automatic valve having an internal valve seat between its admission pipe and the valve chest, a plug for said valve seat, a piston connected with the plug above the admission to the automatic valve, said piston being slightly larger than the plug, a still larger piston connected with said plug above the piston first mentioned,

there being a tubular opening through the 10 pistons and plug leading from below the plug to a point above the larger piston, whereby steam chest pressure may act downwardly on the larger piston.

In testimony whereof, I hereunto affix my signature.

RALPH M. LICKLEY
